MATCH BOOK

Joseph F. St. John, Chicago, Ill.

Application January 26, 1934, Serial No. 708,467

2 Claims. (Cl. 206—29)

This invention relates to certain new and useful improvements in match books of that general character which embodies a novel construction and arrangement of elements, and these so disposed as to do away with the pinching, or pressing, as well as avoiding pinching of the opposed faces of the match members against each other, and also does away with the usual manner of lighting the match, in that the opposed faces 5 of the material at one end of the book are permanently adhered together, the opposed faces at the other end being unattached to each other so that the free end may be turned aside to permit ready access to the match to break it from 10 its body portion, after which, the head of the match is inserted between the opposed portions and readily ignited by friction on the igniting material.

Another advantage resides in the fact that the 20 ignition material is entirely enclosed and protected from dampness so that the matches can be relied upon as always kept dry, which will be found a great advantage over match holders of the known type.

25 The form of matchbook in question broadly embodies the following features, which when present, lessen the cost of manufacture of the device: attractive appearance, as well as of such structural nature as to permit it to be carried in the 30 pocket with safety particularly against ignition.

Other objects and advantages of my improved construction will be more fully hereinafter set forth and defined in the claims.

The present invention is clearly illustrated in 35 the accompanying drawing, which, with the numerals of reference, will be found to readily bring out the details upon which the claims are based, and which form a part of this application in which

40 Figure 1 is a perspective view of my improved match book, with the back open, and matches shown in position to be broken off and the head of the match then engaged with the igniting material.

45 Figure 2 is an edge view of the book as placed upon the market.

Figure 3 is a face view of the match box open, before the matches are inserted.

Figure 4 is a face view of the book closed.

50 Figure 5 is a view, showing the retainer, or book, open, and a match, with a portion of the stem broken off, and the head of the match in position to be drawn lengthwise of the abrasive member, by which movement the match will be ignited.

Like numerals of reference indicate like parts throughout the several views.

Referring to the details of construction of my improved match book, with the understanding that the invention is not to be limited to the details of construction herein shown and now to be described, but intended to be capable of changes in construction so long as they come within the scope of the appended claims.

1 designates the book, as a whole; it comprises 10 the portions 2, 3 and 4, of any suitable material, folded along the line 5, at one end, and a narrower member 6, at the other end as seen clearly in Figure 1.

The member, or portion 4, may be secured to 15 the member 2, or formed integral therewith, as may be thought best, but, in either event, the construction is such that slight flexibility or movement should be provided at each end of the member 4 to allow limited movement of the member 20 4 when a match is about to be ignited. In the present instance only the ends are cut as will be seen clearly in Figure 3: only the end portions are cut, the middle portion remaining uncut as 25 seen best in Figure 3, and indicated in Figures 4 and 5.

Adjacent portions of the members 4 and 2 at the closed end are provided with any suitable adhesive as seen at the lower end of the folded portion of the adjacent members, as seen best 30 in Figure 3.

It will be noted that by the arrangement and disposition of parts as above described, the short severance of the adjacent ends of the elements 2 and 4 provide sufficient space for the entry of the 35 match head end into the space between the opposed members. When the head of the match is inserted as seen in Figure 5 all that is necessary is to give the match a pull and the contact of the head with the friction member insures lighting of 40 the match.

The ignition material is entirely enclosed between the cuts in the ends of the member 4, hence dampness cannot affect the same, so that the matches will always light readily and easily, 45 when inserted and pulled out. The members will always perform their proposed functions, and the match book will close tightly when not in use, which will be found to be a great advantage.

Modifications in detail may be resorted to without departing from the spirit of the invention, or sacrificing any of its advantages.

What is claimed as new is:—

1. A safety match folder comprising a card of matches and a cover encompassing said card,

said cover being folded to provide a back and overlapping front flaps, the lower front flap and said back embracing the lower edge of said card in fixed relation, the fold line portion between said back and said lower front flap being slit inwardly from the side edges thereof, the inner opposite portions bounding the said slit being surfaced with match-igniting material.

5 2. A safety match folder comprising a cover for encompassing the card, said cover being folded

to provide a back and overlapping front flaps, the lower front flap and said back embracing the lower edge of said card in fixed relation, the fold line portion between said back and said lower front flap being slit inwardly from the side edges thereof, the inner opposite portions bounding the said slits being surfaced with match-igniting material.

JOSEPH F. ST. JOHN.
